UNITED STATES PATENT OFFICE.

TONEY PIRO, OF PEKIN, ILLINOIS.

ADJUSTABLE PIPE WRENCH AND HANDLE THEREFOR.

Application filed April 2, 1924. Serial No. 703,712.

To all whom it may concern:

Be it known that I, TONEY PIRO, a citizen of the United States, residing at Pekin, in the county of Tazewell and State of Illinois, have invented certain new and useful Improvements in Adjustable Pipe Wrenches and Handles Therefor, of which the following is a specification.

This invention relates to new and useful improvements in wrenches which are particularly adapted for use upon cylindrical objects such as pipes or the like and has for its principal object to provide a simple and efficient device which will be positive in its gripping action, means being further provided for enabling the wrench to be actuated in positions which are ordinarily inaccessible.

A still further object of the invention is to provide a device of the above mentioned character, wherein the jaws may be moved relative to each other for engagement with the object to be turned in an easy and quick manner, a handle being detachably and adjustably associated with the shank of the wrench for facilitating the actuation thereof from various positions.

Another important object of the invention is to provide a wrench of the above mentioned character, wherein the shank is provided with a polygonal-shaped socket member for receiving the polygonal-shaped head of a handle whereby the handle may be actuated from various angles, these being further associated with the handle and the polygonal socket member for holding the handle against accidental displacement from the shank when in use.

A still further object of the invention is to provide a device of the above mentioned character, which is simple in construction, inexpensive, strong and durable, and further well adapted for the purposes for which it is designated.

Other objects and advantages of this invention will become apparent during the course of the following description.

In the accompanying drawings forming a part of this specification, and in which like numerals designate like parts throughout the same,

Figure 1 is a side elevation of my im-

proved wrench with the handle in position thereon,

Figure 2 is a top plan view thereof with the handle disposed at substantially right angles to the shank,

Figure 3 is a sectional view taken approximately on line 3—3 of Figure 1,

Figure 4 is a sectional view taken approximately on line 4—4 of Figure 2,

Figure 5 is a sectional view taken on line 5—5 of Figure 1,

Figure 6 is a horizontal section of the shank showing the teeth formed on the sides of the longitudinal slot provided in the shank and also showing the polygonal shaped socket member on one end and the gripping jaw on the other end thereof,

Figure 7 is a detail perspective view of the block supported in the handle for holding the latch member,

Figure 8 is a perspective view of the latch member, and

Figure 9 is a plan view of an auxiliary handle.

In the drawings wherein for the purpose of illustration is shown the preferred embodiment of my invention, the numeral 1 designates the shank and adapted to be detachably supported in the outer end thereof is the gripping jaw 2. Any suitable fastening means such as is shown at 3 in the drawings is provided for holding the gripping jaw in position on the outer end of the shank. The gripping jaw 2 is provided with the teeth 4 which extend transversely across the outer face thereof in the manner as clearly shown in Figure 1 of the drawings. The opposite end of the shank 1 is provided

with the polygonal shaped socket member 5 which is also provided with the polygonal shaped transversely extending opening or socket 6 the purpose of which will be hereinafter more fully described. The shank 1 is further provided with the longitudinally extending slot 7 which extends through the sides of the same, and the bottom edge of the slot 7 is provided with the teeth 8 in the manner as clearly shown in Figures 1 and 6 of the drawings.

Adapted to co-operate with the gripping jaw 2 is the co-acting gripping jaw 9 which is formed on the outer end of the arm 10

in the manner as shown more clearly in Figure 1 of the drawings. The gripping jaw 9 is also provided with teeth 11 for co-operation with the teeth 4 on the gripping jaw 2 for securely holding the cylindrical object in position therebetween so as to prevent the accidental displacement or slipping of the gripping jaw around the object which is to be turned. The inner end of the arm 10 is provided with a sleeve 12 which has an enlarged opening 13 extending longitudinally therethrough and providing a means for receiving the shank 1 thus permitting the sliding movement of the arm and the jaw 9 carried on the outer end thereof on the shank in the manner as will be hereinafter more fully described.

The front wall or side of the sleeve 12 is provided with the enlarged opening 14 which is of substantially the same width as the slot 7 provided in the shank 1 and is provided for the purpose to be presently apparent. The rear wall of the sleeve 12 is provided with a threaded opening 15 which is also in alignment with the slot 7 in the manner as clearly shown in Figures 3 and 5 of the drawings. Adapted to extend through the opening 14 in the front wall of the sleeve 12 and disposed between the upper edge of the longitudinal slot 7 and the teeth 8 formed in the bottom edge thereof is the pinion 16. The pinion 16 has teeth 17 meshing with the teeth 8 formed in the bottom of the slot 7 and the outer end of the pinion 16 is provided with the knurled handle 18 whereby the same is to be operated.

Extending through the pinion 16 for the purpose of securing the same in position in the sleeve, is the fastening bolt 19 the inner end of which is threaded as shown at 20 for engagement with the threaded opening 15 provided in the rear wall of the sleeve, and a shoulder such as is shown at 21 in the drawings with reference more particularly to Figure 3 is formed on the bolt 19 adjacent the threaded end thereof for engagement with the inner end of the pinion 16. The fastening bolt 19 extends through the central opening provided in the pinion and the outer end of the fastening bolt is provided with the knurled slotted head 22 which is receivable in the cut-out portion I provided in the knurled head 18 of the pinion 16. In this manner, the pinion 16 will be securely held in position in the sleeve and in engagement with the teeth in the shank whereby the arm 10 may be moved in either direction so as to cause the jaw 9 to move inwardly or outwardly with respect to the stationary jaw 2. The portion of the pinion 16 adjacent the handle 18 formed on the outer end thereof is provided with a circumferentially extending groove 24 and extending therein is the spring-pressed member 25 which is supported in the sleeve 12 in the

manner as shown in Figure 5 of the drawings and the purpose of this construction is to provide a means for preventing the pinion from being freely rotated, the device acting as a friction holding means for the pinion. By operating the knurled handle 18 the pinion may be caused to travel in the groove 7 over the serrated bottom thereof and simultaneously move the arm and jaw 9 carried thereby in either direction on the shank until the object to be turned is gripped by the jaws 2 and 9, respectively.

For the purpose of actuating the wrench after the gripping jaws have been placed in position around the pipe or other cylindrical object to be turned, I provide the handle 26. The forward end of the handle 26 is provided with a polygonal-shaped head 27 which is disposed at substantially right angles to the body portion of the handle in the manner as clearly shown in Figures 1 and 4 of the drawings. The polygonal head 27 is adapted to be disposed within the polygonal-shaped socket 6 provided in the end of the shank 1 and may be so arranged therein as to enable the handle to be placed at a desired angle with respect to the shank. In Figure 1 of the drawings the handle 26 is disposed substantially in the same plane as the shank while in Figure 2 of the drawings the handle 26 is disposed at substantially right angles thereto. By providing the handle with the polygonal-shaped head 27 and the shank 1 with the polygonal-shaped socket 6 the various angles in which the handle may be supported on the shank, are provided.

For the purpose of preventing the accidental removal of the handle from the shank, I provide the forward end thereof with a suitable pocket in which is adapted to be removably supported a rectangular shaped block 28 the construction of which is more clearly shown in Figure 7 of the drawings. This block 8 is provided with the longitudinally extending slot 29 for co-operation with a slot 30 provided in the forward end of the handle 26 and any suitable fastening means such as is shown at 31 is adapted to extend through the openings 32 provided in the block and in the pocket formed in the forward end of the handle for holding the block in position thereon. Adapted to be supported by the block 28 and the forward end of the handle 26 is the latch 33 the construction of which is clearly shown in Figure 8 of the drawings, the latch being of substantially angular construction. The forward end of the latch is adapted to be disposed through an opening provided in the forward end of the handle and is adapted to be seated in one of the recesses 34 provided in the outer faces of the polygonal-shaped socket member 5. A coil spring 35 which is disposed in the slot 30

normally holds the forward end of the latch 33 in engagement with the socket member and for the purpose of retracting the latch from engagement with one of the recesses, 5 the depending portion which extends through the slot 29 of the block 28 is provided with a head 36.

When the latch is in a retracted position, the polygonal-shaped head 27 of the handle 10 26 may be placed in the polygonal socket 6 at the desired angle and when the same is seated in the socket the spring 35 will normally urge the forward end of the latch into engagement with the adjacent recess 15 34, thus holding the handle in locked engagement with the socket member 5 and against vertical displacement therefrom.

By providing a handle connection of the above mentioned character, the wrench may 20 be operated from any convenient position in a simple and efficient manner. Heretofore, considerable difficulty has been experienced in turning pipes where insufficient room was provided for enabling the handle 25 of the wrench to be readily grasped by the operator for turning the wrench. However by providing a handle connection of the character above described, the wrench may be easily turned regardless of the position 30 in which the same is placed and without having the person operating the wrench experience difficulty in reaching the handle whereby the wrench may be turned.

If, however, it is desired to further render the operation of the handle of the wrench more easily and in instances where the operation of the handle 36 would not be very efficient, I provide the auxiliary handle shown at 37 in Figure 9 of the drawings. One end of the handle 37 is provided 40 with a slot 38 which provides a means for permitting the same to extend over the free end of the handle 26 and will be disposed at substantially right angles thereto, thus 45 lengthening the leverage of the wrench and permitting the operator to actuate the same from a distant point without any difficulty.

By having the teeth 8 provided in the bottom of the slot 7 wherein the teeth extend 50 slightly less than one half the width of the slot and the other portion of the bottom of the slot will cooperate with the smooth portion of the pinion thereby causing the latter to act as a roller bearing thus 55 relieving the pressure from the teeth when the wrench is in use.

An adjustable pipe wrench of the above mentioned character, will not only be strong and durable, but may further be 60 manufactured at a very low cost and the parts are so arranged as to enable the same to be readily disassembled whenever necessary.

While I have shown the preferred embodiment of my invention, it is to be under-

stood that various changes in the size, shape and arrangement of parts may be resorted to without departing from the spirit of the invention and the scope of the appended claims.

Having thus described my invention, what I claim is:

1. A wrench of the class described comprising a shank, a jaw on the outer end thereof, a co-acting jaw slidable on said shank, means for adjusting said jaws relative to each other, a socket member formed on the opposite end of said shank, said socket member having a polygonal-shaped socket formed therein at substantially right angles to the shank, a handle having a polygonal-shaped head adapted to fit in said polygonal-shaped socket, and means for locking said handle against vertical movement on said shank.

2. A wrench comprising a shank, a jaw at one end thereof, a co-acting jaw slidable on said shank, means for adjusting said jaws relative to each other, a polygonal-shaped socket member formed on the opposite end of said shank, said polygonal-shaped socket member having recesses provided in the outer faces thereof and having a polygonal-shaped socket extending at right angles to the shank, a handle having a polygonal-shaped head adapted to fit in said polygonal-shaped socket, and means for locking said handle on said shank against vertical movement thereof, comprising a spring-pressed latch extending forwardly from the inner end of the handle and adapted to fit in one of said recesses.

3. A wrench comprising a shank, a jaw on the outer end thereof, said shank having a longitudinally extending slot formed therethrough, one of the longitudinal edges of the slot having teeth thereon, an arm, a jaw on the outer end thereof co-acting with the aforementioned jaw, a sleeve on the inner end of said arm and slidably supported on said shank, said sleeve having an opening provided in the front face thereof co-operating with the slot in said shank, and being further provided with a threaded opening in the rear face thereof, a hollow pinion extending through the opening in the front of said sleeve and disposed in said slot, the teeth of said pinion meshing with the teeth in said slot, a handle formed on the outer end of said hollow pinion for actuating the same, a fastening member extending through the pinion and having its inner end threaded into the threaded opening provided in the rear face of the sleeve, the head of said fastening member receivable in an opening provided in the head of said pinion, for securing the pinion in position in the sleeve and in the slot in the shank, and means associated with the inner end of the shank 110 for actuating the same.

125

130

4. A wrench comprising a shank, a jaw on the outer end thereof, said shank having a longitudinally extending slot formed therethrough, one of the longitudinal edges 5 of the slot having teeth thereon, an arm, a jaw on the outer end thereof co-acting with the aforementioned jaw, a sleeve on the inner end of said arm and slidably supported on said shank, said sleeve having an 10 opening provided in the front face thereof co-operating with the slot in said shank, and being further provided with a threaded opening in the rear face thereof, a hollow pinion extending through the opening in the 15 front of said sleeve and disposed in said slot, the teeth of said pinion meshing with the teeth in said slot, a handle formed on the outer end of said hollow pinion for actuating the same, a fastening member extending through the pinion and having its inner end threaded into the threaded opening provided in the rear face of the sleeve, the head of said fastening member receivable in an opening provided in the head of 20 said pinion, for securing the pinion in position in the sleeve and in the slot in the shank, means for frictionally holding the pinion in said sleeve, and means associated with the inner end of the shank for actuating the same. 25

In testimony whereof I affix my signature.
TONEY PIRO. 30
